UNITED STATES PATENT OFFICE.

JOHN FLOOD, OF ASHTABULA, OHIO.

FURNACE ATTACHMENT.

1,033,571.

Specification of Letters Patent.

Patented July 23, 1912.

Application filed November 14, 1910. Serial No. 592,372.

To all whom it may concern:

Be it known that I, JOHN FLOOD, a citizen of the United States, residing at Ashtabula, in the county of Ashtabula and State 5 of Ohio, have invented certain new and useful Improvements in Furnace Attachments; and I do declare the following to be a full, clear, and exact description of the invention, such as will enable others skilled in the art 10 to which it appertains to make and use the same.

This invention relates to attachments for furnaces.

One object of the invention is to provide 15 an attachment for furnaces whereby the waste heat radiating from the sides of the furnace and from the smoke and heat conducting pipes is retained and utilized for increasing the heat of the furnace and at the 20 same time keeping the furnace room or cellar cool.

Another object is to provide means for controlling and regulating the waste heat collected by the attachment.

25 With the foregoing and other objects in view, the invention consists of certain novel features of construction, combination and arrangement of parts as will be more fully described and particularly pointed out in 30 the appended claims.

In the accompanying drawings: Figure 1 is a diagrammatic view of a furnace and portion of a building showing the application 35 of the invention; Fig. 2 is a vertical sectional view of the upper portion of the furnace with the attachment applied thereto; Fig. 3 is a horizontal section of the same taken on the line 3—3 of Fig. 2; Fig. 4 is an enlarged vertical section on the line 40 4—4 of Fig. 2.

Referring more particularly to the drawings, 1 denotes a furnace casing, 2 one of the hot air conducting pipes and 3 the smoke pipe of a furnace. These parts may be of 45 the usual or any desired construction.

Arranged around the upper portion of the furnace casing 1 and spaced a suitable distance therefrom is an asbestos heat collecting jacket 4, the upper end of which projects a suitable distance above the top of the furnace casing and has arranged therein a head or top 5, which is set below the upper edge of the jacket and spaced a suitable distance above the top of the furnace casing, 50 preferably by spacing lugs 6, to form a hot air collecting space 7. The space formed by

the extending upper edges of the jacket 4 above the top 5 is filled with mineral wool or other non-heat-conducting material. The lower end of the jacket 4 is drawn inwardly 60 and securely bound or fastened to the outer side of the casing 1 by a lower clamping band 8, while the upper end of the jacket has engaged therewith an upper clamping band 9. At the front side of the furnace 65 the jacket is cut out and secured to the adjacent surface of the furnace casing 1 in any suitable manner to provide access to the doors of the furnace. In the sides of the jacket where the same is drawn in at its 70 lower edge and fastened to the lower casing is formed a series of cold air inlet ports or passages 10, through which cold air passes and is heated in the jacket by the heat radiating from the sides of the casing. 75

The hot-air conducting pipes 2, one of which is shown in the drawings, are each provided with an asbestos jacket 11, said jackets being spaced a suitable distance from the outer sides of the pipe to form an 80 air space which is open at the inner end of the jacket or this end may be provided with a series of cold air inlet passages. In the upper side of the outer portion of the pipe 2 or at the point where the elbow is engaged therewith to connect the pipe to the heating pipe leading to the register is formed a hot air inlet passage 12 below which in the adjacent end of the pipe is arranged an inclined heat deflecting plate 13 85 by means of which the hot air from the space between the jacket and the pipe is admitted and directed on through the pipe, while the hot air from the furnace will be prevented from passing out of the aperture 12 and will be directed on up through the 90 pipe to the register.

Connected at one end to the inner end of the pipe 2 and at its opposite end to the jacket 4 is a hot air conducting pipe 14 by 100 means of which the hot air accumulating in the upper portion of the space formed between the furnace jacket 4 and the casing 1 is conducted and discharged into the hot air 105 pipe 2. In the pipe 14 is arranged a damper 15 by means of which the passage of the heated air from the space formed by the jacket 4 to the hot air pipe 2 is controlled. In the inner end of the pipe 2 is also arranged the usual heat controlling damper 16 whereby the hot-air passing through the 110 pipe 2 from the furnace is controlled.

The smoke pipe 3 is also provided with an asbestos jacket 16' which is spaced a suitable distance from the smoke pipe and is open at its inner end and closed at its 5 outer end as shown. With the jacket 16' near its outer end is connected a hot air conducting pipe 17 the inner end of which is connected to the jacket 4 opposite to the hot air collecting space 7 arranged between the 10 upper end of the furnace casing and the top 5 of the jacket as shown.

By thus inclosing the furnace and the hot-air and smoke conducting pipes it will be readily seen that all of the heat radiating 15 from these parts will be collected and conducted to the registers thereby greatly increasing the heating capacity of the furnace and reducing the amount of fuel required. It will also be seen that by inclosing 20 the furnace and the hot-air conducting pipes in the manner described the furnace will be prevented from heating the furnace room or cellar in which the same is located.

From the foregoing description taken in 25 connection with the accompanying drawings, the construction and operation of the invention will be readily understood without requiring a more extended explanation.

Various changes in the form proportion 30 and the minor details of construction may be resorted to without departing from the principle or sacrificing any of the advantages of the invention as defined in the appended claims.

35 Having thus described my invention, what I claim is:

1. An attachment for furnaces comprising a furnace jacket of non-heat conducting material, said jacket surrounding the furnace casing and spaced therefrom and having 40 at its lower portion air openings, means to secure said jacket to the furnace casing, smoke and hot air pipes, non-heat radiating jackets arranged around the pipes and spaced therefrom, said jackets being open 45 at their lower ends, a hot air conducting pipe connecting the jacket on the smoke

pipe with the jacket of the furnace, a hot air conducting pipe adapted to connect the upper portion of the space between the furnace casing and its jacket with the jacket of the hot air pipe, means whereby the hot air collected by the jacket around the hot air pipe is admitted to said hot air pipe and conducted thereby to a register, and a 50 damper to control the passage of the hot air from the space between the furnace casing and its jacket. 55

2. An attachment for furnaces comprising an asbestos jacket arranged around the furnace casing and spaced from said casing and having at its lower end air inlet openings, a top arranged in the upper end of said jacket and spaced a suitable distance above the top of the furnace casing, a filling 60 of non-heat conducting material forming the top of said jacket, a hot air conducting pipe connected to the furnace casing and having near its outer end a hot air inlet passage, a heat deflecting plate arranged below said 65 passage, an asbestos jacket arranged around said pipe and spaced therefrom to form a heat controlling and conducting space, said jacket being closed at its upper end and open at its lower end, a hot air conducting 70 pipe to connect the lower end of said jacket with the upper portion of the jacket surrounding the furnace casing, a hot air controlling damper arranged in said pipe, a hot air collecting jacket arranged around 75 said space and spaced a suitable distance from the smoke pipe of the furnace, a hot air conducting pipe to connect the upper end of said smoke pipe jacket with the furnace 80 casing jacket, whereby the hot air collected by the smoke pipe jacket is conducted to the space inclosed by the furnace casing jacket. 85

In testimony whereof I have hereunto set my hand in presence of two subscribing witnesses.

JOHN FLOOD.
